(57) **CLAIM**

The ornamental design for a trash bin, as shown and described.

DESCRIPTION

FIG. 1 is a front perspective view showing a first embodiment of our trash bin;

FIG. 2 is a front plan view of our trash bin of FIG. 1;

FIG. 3 is a left side plan view of our trash bin of FIG. 1;

FIG. 4 is a left side plan view of our trash bin of FIG. 1;

FIG. 5 is a rear plan view of our trash bin of FIG. 1;

FIG. 6 is a top view of our trash bin of FIG. 1;

FIG. 7 is a front perspective view showing a second embodiment of our trash bin;

FIG. 8 is a front plan view of our trash bin of FIG. 7;

FIG. 9 is a left side plan view of our trash bin of FIG. 7;

FIG. 10 is a left side plan view of our trash bin of FIG. 7;

FIG. 11 is a rear plan view of our trash bin of FIG. 7; and,

FIG. 12 is a top view of our trash bin of FIG. 7.

The broken lines in FIGS. 5 and 11 depict portions of the trash bin that form no part of the claimed design.
